UNITED STATES PATENT OFFICE.

JOHN M. CHERRY, OF WESTFIELD, NEW JERSEY.

MOVABLE PLATFORM FOR THE STERN END OF CAR-FLOATS.

1,249,719.

Specification of Letters Patent. Patented Dec. 11, 1917.

Application filed May 14, 1917. Serial No. 168,578.

To all whom it may concern:

Be it known that I, JOHN M. CHERRY, a citizen of the United States, residing at Westfield, in the county of Union and State 5 of New Jersey, have invented a new and useful Improvement in a Movable Platform for the Stern End of Car-Floats, of which the following is a specification.

This invention relates broadly to gang 10 planks, and more particularly to a movable platform for the end of car floats.

The principal object of the present invention is to dispense with the fixed platforms or planks ordinarily connecting the car float 15 with the dock, wharf or the like, and to substitute a movable platform so mounted that it can be adjusted to various heights as conditions may require.

Still another object of the present invention is to provide a car float with a movable platform as described, and to protect the entire platform by a roof, one end of which is pivotally supported and connected to the movable platform so that the two may be 25 moved in unison to maintain at all times the proper distance between the platform and the roof.

Still another object of the invention is to provide a counterbalancing mechanism for 30 a platform and roof of this type so that the same may be easily adjusted as required.

These and other objects, together with attendant advantages will be obvious as the invention becomes better understood by reference to the specification, and drawings 35 forming a part thereof, throughout the several views of which like characters of reference have been used to indicate like parts.

Referring to the drawings,—

Figure 1 is a side elevation of a portion 40 of a car float equipped with my improved platforms.

Fig. 2 is an end elevation of the construction shown in Fig. 1.

Fig. 3 is a plan view showing the pivotal 45 mountings of my improved platforms.

Fig. 4 is a diagrammatic view showing the method of attaching the parts to the car float.

It has heretofore been customary to equip 50 car floats with stationary platforms over which the material carried by the cars was unloaded. These platforms have been objectionable for the reason that due to 55 changes in the tidal condition of the waters in which the car float is operating, the plat-

form is not always at the proper elevation. To remedy this it has been necessary to provide planks or the like which were laid from the wharf to the car float. My invention 60 overcomes the difficulties encountered in such constructions and provides a platform which is at all times protected from the weather, and is adjustable to meet the varying conditions of usage to which it is subjected. 65

Referring more particularly to the drawings, I have shown a car float 1 of ordinary construction having mounted thereon a plurality of vertical standards 2 adapted 70 to support platforms 4 extending the entire length of the car float at such a height above the same as to be substantially level with the car floors carried thereby. The standards also support a roof 5 adapted to protect both the contents of the cars, and the stevedores engaged in the unloading of the same, from the weather. It will be apparent that the roof and platform may be constructed and supported in any desired manner. 75

On the end of the float opposite that from which the cars pass onto the same, and which for sake of convenience will herein-after be designated the rear end of the float, 80 are mounted movable platforms 6, hingedly supported by means of pivots 7 to the platforms extending alongside of and between the cars. As shown clearly in Fig. 3, the movable platforms have a separate connection with each of the unloading platforms, these connections lying at a point adjacent the door of the car lying nearest the rear end of the float. The relative arrangement of parts is clearly shown in Fig. 4 wherein 85 a car is indicated in dotted lines in a position to be unloaded. Adjacent the rear end of the car float are pairs of parallel uprights 8 connected by cross bars 9, and maintained in spaced relation by means of 90 a cross brace 10. Mounted on the cross braces 10 are pulleys 11 journaled on shafts 12 adapted to be driven by worm wheels 14. Extending beneath the brace 10 is a driving shaft 15 having its opposite ends journaled in hangers 16 carried by the uprights, and carrying a worm 17 adjacent each end in mesh with the worm wheels 14. For rotating the shaft 15 and the worm wheels 14, the shaft is provided with a pulley 18 around 105 which passes a hand rope or chain 19.

The platform is adjustably carried and

counter-balanced by means of cables 20 secured to the platform and passing over the pulleys 11, their opposite ends being secured to counter-weights 21 slideable between the uprights 8 which form guides therefor. By reason of this construction it will be apparent that the platform may be readily raised or lowered as conditions may require by simply manipulating the hand chain 19.

10 For protecting the merchandise and stevedores during loading and unloading operations, the roof 5 is provided with hinged portions 22 overlying the movable platform and connected thereto by links 24 so as to 15 have a movement in unison with the platform. The entire construction may be braced in any desired manner by suitable braces 25. In some instances I have found it desirable to provide notches or sockets 26 20 in the platform 6 to receive the hooks ordinarily formed on the lower surfaces of small bridges or gang planks. Such bridges or gang planks when used constitute a continuation of the platform while in any position, so that the goods may be easily unloaded from the float.

While I have described the preferred form of my invention, it will be obvious that changes may be made in the mechanical 30 construction thereof without departing from the scope of the appended claims.

What I claim is—

1. A car float having a loading and unloading platform formed thereon so as to 35 extend in substantially the plane of the car floors on the float, a movable platform secured thereto adjacent the doorway of the end car on the float, means for counter-balancing the weight of said movable plat-

form, and means for adjusting said movable 40 platform at will.

2. A car float having a loading and unloading platform formed thereon and overlying the floor so as to lie in substantially the plane of the floors of the cars on the 45 float, a movable platform secured thereto, and means for adjusting said movable platform.

3. A car float having a loading and unloading platform formed thereon, a movable 50 platform secured thereto, means for adjusting said movable platform, and an adjustable covering section for protecting said movable platform in all of its different adjusted positions.

4. A car float having a loading and unloading platform formed thereon and extending longitudinally thereof, a roof protecting said platform, a movable platform secured to said first-mentioned platform, a hinged roof section, and means for adjusting said platform and roof section simultaneously.

5. A car float having a loading and unloading platform formed thereon and extending longitudinally thereof, a roof protecting said platform, a movable platform secured to said first-mentioned platform, a hinged roof section, means connecting said movable platform and said roof section to 70 cause the same to move in unison, means for moving the same, and means for counter-balancing the weight thereof.

JOHN M. CHERRY.
